UNITED STATES PATENT OFFICE.

ALDEN L. HOWELL, OF GALLIPOLIS, OHIO.

FLOOR-KEY FOR VALVES.

1,287,320.

Specification of Letters Patent. Patented Dec. 10, 1918.

Application filed November 24, 1917. Serial No. 203,725.

To all whom it may concern:

Be it known that I, ALDEN L. HOWELL, a citizen of the United States, residing at Gallipolis, in the county of Gallia and State of Ohio, have invented a new and useful Floor-Key for Valves, of which the following is a specification.

The present invention relates to valves, and more particularly to a key adapted for 10 opening and closing the valve, particularly when used in gas pipes and the like.

An object of the present invention is to provide a key adapted for use in opening and closing valves located beneath the floor, 15 or the like, and which embodies a structure such that the key may be readily adjusted to cover the opening in the floor above the valve and thus house the same.

Another object of the present invention is 20 to provide a key and a cover plate structure combined which may be permanently fitted to the valve so as to retain the key at all times in place for use, the structure admitting the ready adjustment of the cover plate 25 into position for use as a key, and being adapted to provide a relatively large finger hold for securing a firm purchase upon the key.

The above, and various other objects and 30 advantages of this invention will be in part described, and in part understood, from the following detailed description of the present preferred embodiment, the same being illustrated in the accompanying drawing wherein:

35 Figure 1 is a top plan view of a combined cover plate and key constructed according to the present invention.

Fig. 2 is a vertical section through the same mounted in the floor and connected to 40 the shank of a valve.

Fig. 3 is a similar view taken axially at right angles to the showing in Fig. 2.

Fig. 4 is a detail perspective view of one section of the cover plate.

45 Fig. 5 is a like view of the other section of the cover plate.

Fig. 6 is a detail perspective view of the socket carried by the cover plate and adapted to engage over the stem of the valve.

50 Referring to the drawing, A designates the floor or ground line beneath which is positioned a valve B interposed in a pipe C adapted as a conduit for gas or other desired fluid, and which is provided with an upwardly projecting valve stem D of non-circu-

lar cross section. Access is gained to the valve B beneath the floor by an opening E formed through the floor A above the valve.

Heretofore openings E have been normally closed by a cover plate which is removed when access is desired to the valve for opening and closing the same, the valve being operated by a separate key which is frequently lost or misplaced.

In the present instance the opening E is 65 counterbored at its upper end to form an upwardly facing shoulder 10 upon which is seated an annular frame or ring 11 secured in the floor A flush with the upper surface thereof by screws 12 or the like which extend diagonally and radially through the ring 11 and into the floor A. The ring 11 has an internal annular shoulder 13 upon which is fitted a cover plate adapted to lie flush with the upper faces of the frame 11 70 and the floor A.

The cover plate is formed of a pair of substantially semicircular disk sections 14 and 15 which are provided with interfitting lugs 16 which are preferably enlarged and rounded and have transverse openings 17 therethrough adapted to transversely align when the sections 14 and 15 are assembled. A pintle 18 is secured through these lugs 16 to hold the cover sections together. 85

The cover section 15 forms a finger hold for the key and has an intermediate lug 16 enlarged transversely of the section and formed with a tongue 19 lying substantially in the plane of the section 15 and adapted to 90 fit into a recess 20 formed in the other section 14. The tongue 19 is adapted to closely fit in the recess 20 and to lie flush with the upper face of the section 14 to provide an uninterrupted cover plate when the sections 14 95 and 15 are in closed position.

The sections 14 and 15 rest at their marginal edge portions upon the shoulder 13 within the frame 11 when the cover plate is closed. Suspended from the cover plate is 100 a non-circular socket 21 adapted to receive the stem D of the valve in its lower end, the opening in the socket 21 flaring upwardly to receive the stem D should the opening E in the floor not register directly 105 and concentrically above the valve B. The socket D is provided with two or more ears 22 which extend upwardly from one side of the socket and are curved inwardly toward the longitudinal axis of the socket. 110

The ears 22 have transverse registered openings 23 in their upper ends and are adapted to interfit between the lugs 16 of the plate sections and to receive the pintle 18 therethrough. The socket 21 is thus hinged upon the cover plate and suspended therefrom in sliding engagement over the valve stem D.

The disk section 14 is adapted to remain in the frame 11 and upon the shoulder 13 thereof when the device is used as a key, the section 14 having at opposite sides circular projections 24 which form continuations of the outer edge portions of the section 14 and are of sufficient length to extend beyond the plane of the greatest diameter of the disk section. These projections 14, bearing upon the shoulder 13, hold the disk 14 to its seat in the frame and admit of the free turning of the disk without binding in or displacement from the frame.

In use, when the device is closed as shown in Figs. 1 and 2, and it is desired to operate the valve B, it is only necessary to press the tongue 19 down when the finger section 15 of the cover is swung up upon the pintle 18 and may be readily grasped between the fingers. The tongue 19 is adapted to strike the inner wall of the socket 21 and hold the disk 15 vertically as shown in dotted lines in Fig. 2. Pressure may now be placed upon the finger section 15 to turn the same about the vertical axis of the socket 21 and open or close the valve B. When the valve is adjusted the section 15 is merely swung back into place in the frame, closing the opening E and disposing the key out of the way without removing it from the valve.

The upwardly flaring socket 21 adapts the device to the stem D of the valve should the opening E be out of register with the valve stem D, the hinged connection of the socket 21 permitting the latter to swing eccentrically during the rotation of the key in opening and closing the valve. The device is thus adapted for practical application under various conditions, comprises but few parts, and may be readily installed.

Various changes and modifications may be made in the details of the above specifically described embodiment of this invention within the scope of the following claims, and without departing from the spirit of this invention.

55. What is claimed is:

1. In a key for operating valves located beneath the floor, the combination of an annular frame adapted to be fitted in the floor over the valve, a cover plate fitted in the frame for closing the same and adapted to turn in the frame, said plate having a

hinged part adapted to be swung up and engaged by the fingers for turning the cover plate, and a socket depending from the cover plate, for engaging the stem of the 65 valve to turn the same with the cover plate.

2. In a key for operating valves located beneath the floor, the combination of a frame adapted to be seated in the floor flush with the upper surface thereof, a cover plate 70 mounted for rotation in the frame and having its upper face flush with the floor, said cover plate having a hinged section formed with a tongue extending into the body portion of the cover plate and adapted to be 75 depressed for lifting the hinged section out of the frame, and a socket depending from the cover plate for engagement with the stem of the valve to turn the same with the cover plate.

3. In a key for operating valves located beneath the floor, the combination of a frame adapted to be seated in the floor flush with the upper surface thereof, a cover plate 80 mounted for rotation in the frame and comprising a pair of hingedly connected sections, one section having a tongue seated in the other section and adapted to be pressed down into the frame for swinging the section with the tongue up above the 85 frame to form a finger hold, and a connecting member depending from the cover plate for connection with the valve to turn the same with the cover plate.

4. In a key for operating valves located 90 below the floor, the combination of a frame adapted to be seated in the floor, a cover plate mounted for rotation in the frame and comprising a pair of semi-circular disk sections having interfitting apertured lugs, a 95 pin engaging through the lugs to hinge the sections together, one of said sections having a tongue in the plane thereof and the other section having a recess adapted to receive the tongue, and a connecting member 100 depending from said pin for interlocking engagement with the valve to turn the same with the plate.

5. In a key for operating valves located 105 below the floor, the combination of a frame adapted to be seated in the floor, a cover plate mounted for rotation in the frame and including a hinged section adapted to be raised to serve as a handhold, and a socket 110 suspended in pivotal relation from the plate 115 and having an upwardly flaring opening adapted to receive the stem of the valve therein and admit of the free turning of the valve with the plate when the latter is out of axial register with the valve.

ALDEN L. HOWELL.
